UNITED STATES PATENT OFFICE

FREDERICK NEWQUIST, OF ESSEX, IOWA

GLAZIER'S POINT

Application filed June 11, 1927. Serial No. 198,220.

The object of my invention is to provide a glazier's point of simple, durable and comparatively inexpensive construction.

More particularly, my invention relates to a glazier's point wherein a portion thereof is adapted to rest against the glass pane, another portion projecting into the wood sash into which the glass pane is to be mounted, and still another portion intermediate of the two portions referred to, which is adapted to rest upon a flat surface of the window sash.

Still another object is to provide an offset intermediate the ends of a glazier's point for providing a shoulder for receiving a tool or the like wherein the glazier's point may be inserted in a window sash without danger of striking the glass pane.

Still another object is to provide a device wherein either end may be used for insertion in the wood and either end used to abut against the glass pane.

Still a further object is to provide an offset in the glazier's point arranged to rest upon a flat surface of the window sash and thus serve as a stop for limiting the amount of insertion of the point into the wood frame or sash.

With these and other objects in view, my invention consists in the construction, arrangement and combination of the various parts of my glazier's point, whereby the objects contemplated are attained, as herein-after more fully set forth, pointed out in my claim, and illustrated in the accompanying drawings, in which:

Figure 1 is a perspective view of my improved glazier's point.

Figure 2 is a plan view of the blank from which the point is formed.

Figure 3 is a perspective view of a window sash with several of the points installed therein.

Figure 4 is a sectional view taken on the line 4-4 of Figure 3, illustrating a tool or the like used for pressing the point into position.

Figure 5 is a sectional view taken on the line 5-5 of Figure 3, disclosing the point in installed position; and

Figure 6 is a sectional view taken on the line 6-6 of Figure 3.

In the accompanying drawings, I have used the reference character A to indicate generally a window sash, which is provided with a pane of glass 10.

The frame, which forms the sash A, is formed with a shoulder 12 against which the glass 10 is designed to rest, as clearly illustrated in the drawings.

After the glass is inserted against the shoulder 12, I use glazier's points B for retaining the glass in position.

My glazier's point is formed of a single blank of material as disclosed in Figure 2 of the drawings.

The point B includes a central body member 14 substantially rectangular in outline, and has a triangular portion 16 upon each side edge of the body portion 14, so that the entire blank from which the point B is formed is substantially diamond-shaped.

The blank of Figure 2 is arranged to be bent upon the dotted lines 18 for arranging the body portion 14 in a substantially horizontal plane with the two triangular ends 16 projecting above and below the body portion 14 and at substantially right angles thereto.

Either of the triangular portions 16 serve as the point for projecting into the wood of the sash A. Either point may rest against the glass for retaining it in position.

After the glass is inserted in the sash 10, a glazier's point B is placed in the position relative to the glass and sash as shown in Figure 4 of the drawings.

A tool or block 20 of any suitable kind may be placed upon the body portion 14 and by forcing it downwardly or tapping the tool with a hammer, one of the triangular ends 16 will be forced into the sash A, while the other point will rest against the glass 10.

The body portion serves as a stop for limiting the amount of insertion of the point into the wood frame. The body portion 14 also serves as a means whereby a tool or the like may be placed thereagainst for forcing the point into position.

It will be noted that by providing the offset or body portion 14, I am able to use a tool

or the like for tapping the point and forcing it into position, reducing to a very minimum, the likelihood of tapping the window and cracking it.

5 The body portion 14, which is offset, provides a suitable portion for engagement when forcing the point into effective position.

After the points have been inserted, then putty 22 is used in the ordinary manner.

10 With my glazier's points, it is a very easy matter to insert them and it is also an easy matter to withdraw them when desired.

Some changes may be made in the construction and arrangement of the various 15 parts of my glazier's point without departing from the real spirit and purpose of my invention, and it is my intention to cover by my claim, any modified forms of structure or use of mechanical equivalents, which may 20 be reasonably included within their scope.

I claim as my invention:

25 A glazier's point comprising a sheet metal member having similar pointed ends of equal length and a comparatively wide central portion, said member being bent so that the pointed ends extend in opposite directions and lie in parallel planes, the central portion forming a shoulder at right angles to the pointed ends, said glazier's point being capable of reversal for the use of either end thereof to enter a window frame and retain a pane 30 of glass therein.

FREDERICK NEWQUIST.
Des Moines, Iowa, June 6, 1927.
